UNITED STATES PATENT OFFICE.

SPENCER G. NEAL, OF NEW YORK, N. Y., ASSIGNOR TO AUTOMATIC STRAIGHT AIR BRAKE COMPANY, OF WILMINGTON, DELAWARE, A CORPORATION OF DELAWARE.

AIR-BRAKE APPARATUS.

Original No. 1,601,582, dated September 28, 1926, Serial No. 9,789, filed February 17, 1925. Application for reissue filed August 3, 1927. Serial No. 210,441.

This invention relates to improvements in triple valves of the Westinghouse type. In triple valves of this type the main piston, the main slide valve and the graduating valve are moved to release and charging position by an increase in brake pipe pressure. Upon a reduction of brake pipe pressure for an application of the brakes the auxiliary reservoir pressure moves the main piston and the connected main and graduating valves into application position and air flows from the auxiliary reservoir to the brake cylinder. When the auxiliary reservoir pressure has been sufficiently reduced through the flow of air to the brake cylinder the brake pipe pressure will move the main piston and the graduating valve to lap position.

One of the important objects of this invention is to provide a triple valve of the standard Westinghouse type with means for securing a graduated release of the brake cylinder pressure.

Another important object of the invention is to provide a standard Westinghouse type of triple valve with an independent supplementary or pilot valve means operated to service position by a reduction in brake pipe pressure, and which in service application position will connect the brake pipe to the brake cylinder; the main valve means comprising the main and graduating valves, controlling communication between the auxiliary reservoir and the brake cylinder.

Another object of the invention is to provide a supplementary or pilot valve which will be controlled in its movements by brake pipe pressure, emergency reservoir pressure and brake cylinder pressure.

Another important object of the invention is to provide means whereby the supplementary or pilot valve will act as a brake cylinder pressure controlling means and ensure a brake cylinder pressure substantially in direct proportion to the brake pipe reduction regardless of brake cylinder piston travel and brake cylinder leakage.

Another object of the invention is to provide a triple valve, of the type herein described, with a release governing valve having two positions, in one of which the main slide valve in release position will bring about a normal full and quick release of the brakes, the release governing valve in its

other position rendering the main slide valve ineffective in release position, the release of brake cylinder pressure then being controlled entirely by the supplementary or pilot valve. 55

Another important object of the invention is to provide means whereby a standard Westinghouse type of freight triple valve in cycling operations will automatically build up the brake cylinder pressure above that which would be normally obtained from a given brake pipe reduction, the said build-up of brake cylinder pressure being wholly dependent upon the rapidity of the cycling operations so that on low grades the brake cylinder pressure will not be built up as 60 65 high as on heavy grades where the cycling operations are frequent and of short duration. The purpose of this automatic build-up of brake cylinder pressure is to avoid the use of manually settable retainers in grade 70 75 braking.

There are many other important objects and advantages of the invention which will hereinafter appear.

In order to simplify the description the 80 various ports and passages will be described in connection with the various operations of the triple valve.

In the drawings, Fig. 1 is a diagrammatic sectional view of the triple valve embodying 85 the invention, the parts being shown in full release and charging position, the release governing valve being in quick release position;

Fig. 2 a view similar to Fig. 1 showing 90 the parts in service position;

Fig. 3 a view similar to Fig. 1 showing the parts in emergency position;

Fig. 4 a detail sectional view of the release governing valve showing the valve in 95 graduated release position; and

Fig. 5 a diagrammatic view of the apparatus.

In Fig. 5, A designates the triple valve; B the auxiliary reservoir; C the brake cylinder; D the emergency reservoir; E the brake pipe; and F the release governing valve stem. 100

Full release and charging position. 105

The system is charged by increasing the brake pipe pressure, as in the present standard Westinghouse type of air braké ap-

paratus. The air pressure from the brake pipe flows through the brake pipe connection 2, the connected passage 3 into the main piston chamber 1. The increasing pressure in chamber 1 forces the main piston 44 inwardly, toward the right hand as viewed in the drawings. Connected to the piston is the usual valve stem 45, said stem extending inwardly through the main slide valve chamber 5 and being connected to the main slide valve 6 and the graduating valve 56 in the usual manner. The piston stem is connected to the main slide valve by a lost motion connection and the graduating valve is connected directly to the said stem as is usual in this type of apparatus. The main slide valve operates on a main slide valve seat through which various ports and passages are formed. With the main piston in full release and charging position a charging groove 4 is uncovered so that air may flow from chamber 1 through said groove past the piston 44 and into the main slide valve chamber 5. The main slide valve chamber is connected directly to the auxiliary reservoir through passage 7. Said chamber 5 is also connected to an emergency reservoir through passage 8, chamber 9 and a port controlled by a spring-pressed check valve 10. The spring 10^a normally holds the check valve seated and the rising pressure in chamber 9 will unseat said valve and open communication between chamber 9 and the emergency reservoir. The auxiliary reservoir and the emergency reservoir will therefore be charged at the same time and at the same rate. From chamber 1 brake pipe air will flow through the passage 11 into brake pipe chamber 12 of the diaphragm structure. The lower wall of chamber 12 is formed by a brake pipe diaphragm 13. Spaced a suitable distance below the diaphragm 13 is a larger brake cylinder diaphragm 53, said diaphragm being considerably larger in area than the brake pipe diaphragm 13. The diaphragms 13 and 53 form the upper and lower walls of a brake cylinder chamber 55. Below the brake cylinder diaphragm 53 is arranged an emergency reservoir diaphragm 16, this diaphragm being of the same area as the brake pipe diaphragm 13. Between the diaphragms 53 and 16 is formed a retention chamber 26; and below the emergency reservoir diaphragm 16 is formed an emergency reservoir chamber 17. This latter chamber is connected to the emergency reservoir by passage 18 so that said chamber will be charged with emergency reservoir air.

The diaphragms 13, 53 and 16 are rigidly connected together at their centers by a stem 13^a and move up and down together. These diaphragms have a limited up and down movement, suitable stops being provided for that purpose. In the brake cyl-

inder equalizing chamber 55 is arranged a horizontal lever 15^a which is pivotally connected to the stem 13^a. One end of said lever is pivotally connected to the valve casing, its other end being connected to a secondary or pilot valve 15, said valve being arranged in a valve chamber 14. The chamber 14 is directly connected to the brake pipe chamber 12 by a passage 14^a so that brake pipe chamber pressure will always be registered in the chamber 14 and the pressures in the chambers 12 and 14 will always be equal.

With the triple valve parts in full release and charging position, with the release governing valve in quick release position, as shown in Fig. 1, the brake cylinder is in direct communication with atmosphere through brake cylinder passage 19, cavity 20 of the main slide valve, passage 21 which leads direct to the release governing valve chamber 22, and from this chamber to atmosphere through port 23 in the release governing valve 57, and main atmospheric port 24.

The check valve 10 is opened for emergency applications of the brakes by means of a piston 30 and a lever 30^a connected thereto and adapted to bear on the projecting end of the valve 10. The piston 30 reciprocates in a chamber 30^b and said chamber is charged from the main slide valve chamber through port 31 and cavity 31^a in the main slide valve and port and passage 32 which leads from the main slide valve seat into chamber 30^b. The piston 30 therefore is subject on one side to the pressure in chamber 9 and on its other side to the pressure in chamber 30^b and said piston remains inoperative in all positions of the main slide valve except the emergency position, as will be hereinafter described.

A chamber 25 is connected by passage 25^a to the retention chamber 26 and is for the purpose of augmenting said chamber 26. The chamber 25 has no function except in graduated release operations, as will be hereinafter described. With the release governing valve in quick release position, as shown in Fig. 1, chamber 25 is vented directly to atmosphere through passage 27, cavity 28 of the release governing valve, and port and passage 29 which leads direct to atmosphere. Chamber 25 is also connected to atmosphere through a small blow down port 25^b which leads to the main slide valve seat and into a cavity 25^c in the main slide valve. The cavity 25^c connects the port 25^b to an atmospheric port 25^d. The chamber 25 is connected by a port 27^a to the main slide valve seat and in the release position of the main slide valve this port registers with the cavity 20 in the main slide valve so that the chamber 25 is directly connected to the brake cylinder port and passage 19.

In emergency application the brake pipe

is vented to atmosphere by opening the emergency brake pipe vent valve 34. This valve is connected to a piston 33 which reciprocates in a chamber 36-36^a. The chamber 36 below the piston 33 is connected directly to the brake pipe by passage 35. The piston 33 is provided with a small leak port 37 through which air will pass from chamber 36 into the chamber 36^a above said piston. Brake pipe pressure will thereby equalize on opposite sides of the piston 33 and the valve 34 will be held closed. A passage 38 leads from the chamber 36^a above the piston 33 to the main slide valve seat. In the emergency position of the main slide valve passage 38 is connected by a cavity 65 in the main slide valve to a port and passage 40 which leads directly into a chamber 39 thereby reducing the pressure in chamber 36^a and permitting the brake pipe pressure in chamber 36 to raise the piston 33 and open the valve 34. In the release and service positions of the main slide valve chamber 39 is connected direct to atmosphere through cavity 41, and secondary atmospheric port 42, as will be more fully hereinafter described. In the service position of the main slide valve this communication is through port 43 and cavity 41.

Service position.

A service application of the brakes is brought about by a service reduction in brake pipe pressure in the usual manner and the pressure in chamber 1 will be reduced below the auxiliary pressure in chamber 5. When a given differential in pressure has been established in these two chambers piston 44 and the stem 45 which is connected thereto, and the main and graduating valves will be moved toward the left by the superior auxiliary reservoir pressure in chamber 5. The initial movement of the piston and the stem 45 will first take up the lost motion between the extension 46 of the stem and the main slide valve. This initial movement will also move the graduating valve to uncover the service port 49 in the main slide valve. Thereafter the main slide valve will move with the piston stem until the piston engages the graduating stem 47 where it will be stopped in service position. The movement of the stem 47 is resisted by the graduating spring 48, said spring having sufficient tension to hold the piston and the main slide valve in service position when a service reduction in brake pipe pressure has been made (see Fig. 2). The movement of the main slide valve to service position closes communication between the brake cylinder passage 19 and the release cavity 20 of the slide valve 6 and the service port 49 is brought into register with the brake cylinder passage 19. Auxiliary reservoir air is then free to flow from chamber

5 direct to the brake cylinder through the passage 50 in the stem 45, port 49 of the main slide valve and the brake cylinder passage 19 which leads direct to the brake cylinder. The size of the service port 49 is such as to permit a reduction of the auxiliary pressure at practically the same rate as a service reduction of brake pipe pressure. The purpose of this uniform reduction of both the brake pipe pressure and the auxiliary reservoir pressure is to prevent a pressure differential on piston 44 that would tend to compress the graduating spring 48, thus preventing the piston and the slide valves operating to emergency position when a brake pipe reduction is made only at a service rate. In this service position of the main slide valve chamber 30^b will be in direct communication with the auxiliary reservoir chamber 5 through passage 32, cavity 31^a and port 31 of the main slide valve and passage 50 in the main slide valve stem, with the result that there will be no movement of the piston 30 and the emergency reservoir will remain sealed. The brake cylinder will be connected to the equalizing chamber 55 of the pilot valve structure through passage 51, cavity 64 of the main slide valve and passage 52 which leads direct to chamber 55. This communication permits the supplementary or pilot valve to both supply and release air from the brake cylinder so long as the main slide valve 6 is in service position.

The reduction of brake pipe pressure in chamber 1 will result in a corresponding reduction of pressure in the brake pipe chamber 12 of the diaphragm structure, resulting in an upward movement of the valve 15. This upward movement results from the reduction of the pressure in chamber 12 below the undisturbed emergency reservoir pressure in chamber 17 beneath the diaphragm 16. When the pilot valve 15 has been moved upwardly into service position brake pipe air will flow to the brake cylinder through port 54 in the pilot valve, equalizing chamber 55, passage 52, cavity 64 of the main slide valve and passage 51 which leads direct into the brake cylinder passage 19. It is therefore clear that in the service position of the main slide valve air will flow to the brake cylinder from auxiliary reservoir through the main slide valve and also from the brake pipe to the brake cylinder through the independent pilot valve. Brake pipe air will be utilized for building up the brake cylinder pressure and a quick serial action will result.

Service lap position.

The means which establishes the dual communication between the auxiliary reservoir and the brake cylinder and the brake pipe and the brake cylinder, are lapped in

dependently of each other. The main valve means controlling communication between the auxiliary reservoir and the brake cylinder is lapped on the volumetric principle where-
6 by the main slide valve and piston will be operated to the right to cause the graduat-
ing valve to cut off communication between chamber 5 and port 49 of the slide valve when the pressure in chamber 5 has been
10 reduced slightly below the brake pipe pressure in chamber 1. This operation, as in the standard Westinghouse type of freight triple valve, takes place when a given volume has been exhausted from the auxiliary
15 reservoir, and the effectiveness in resultant brake cylinder pressure is determined by the length of the brake cylinder piston travel, which of course, governs the brake cylinder volume. The connection between
20 the brake pipe and the brake cylinder controlled by the secondary valve means is closed when a given brake cylinder pressure has been developed, this pressure being registered at all times in the equalizing chamber 55 and when this pressure is raised to a point where the reduced brake pipe pressure in chamber 12 and the increase in pressure in the equalizing chamber 55 will oppose the undisturbed emergency reservoir
25 pressure in chamber 17, the pilot valve will be moved downward to lap position and the service port of the pilot valve will be closed. Should the piston travel be short or less than normal (8") an abnormal brake cylinder pressure will be developed before the
30 graduating valve 56 will be lapped, and the pressure in the equalizing chamber 55 between diaphragms 13 and 53 will likewise be abnormal. The diaphragms will be lowered
35 and the pilot valve will be moved to release position and communication will be established between the brake cylinder and atmosphere so that the abnormal, developed, brake cylinder pressure will be reduced to
40 normal pressure by the balancing operation of the diaphragms. Should the piston travel be greater than normal the flow of auxiliary reservoir pressure to the brake cylinder will not develop a normal pressure
45 therein, with the result that the pilot valve will be raised to or held in service position by the diaphragms and brake pipe pressure will then flow to the brake cylinder to make up any pressure which was lacking at the
50 time the graduating valve assumed lap position. The operation of the pilot valve as just described, will of course tend to reduce the brake pipe pressure which in turn will if sufficient, again operate the graduat-
55 ing valve and piston to service position, so that the additional air required to develop normal brake cylinder pressure where there is an abnormally long piston travel will be taken from both the auxiliary reservoir and
60 the brake pipe. If the brake pipe pressure
65

is held constantly at any predetermined service reduction, the brake cylinder will be maintained against leakage by the dia-
phragm operated pilot valve 15 alone; but should another service brake pipe reduction
70 be made, air pressure will flow to the brake cylinder both from the auxiliary reservoir and the brake pipe.

Quick release.

75

The release governing valve 57 is ar-
ranged to be manually operated by means of the stem 57^a. This valve has two posi-
tions, a quick release position and a gradu-
ated release position. In its quick release
80 position the large release port 23 connects the release governing valve chamber 22 to the large atmospheric port 24. This position of the valve is illustrated in Fig. 1.

A release of brake cylinder pressure is obtained by increasing the brake pipe pres-
sure in the usual manner. When the brake pipe pressure is raised in chamber 1 to ex-
ceed the pressure in the auxiliary reservoir
chamber 5 sufficiently to operate the piston
90 and the main slide valve to release position
communication will be established from the
brake cylinder direct to atmosphere through
the release cavity 20 of the main slide valve
and thence to atmosphere through the re-
lease governing valve chamber 22 as de-
scribed in connection with the charging of
the system. The auxiliary reservoir will be
recharged from the brake pipe through the
charging groove 4 as hereinbefore described.
100 It will not be necessary, however, to charge
the emergency reservoir because the air in
said reservoir has been maintained undis-
turbed. The movement of the main slide
valve to release position carries the cavity
105 64 out of register with the ports 51 and 52
thereby preventing the pilot valve from
feeding brake pipe pressure to the brake cyl-
inder when the brake pipe pressure is raised
at a slow rate for release of the brakes.
110 The increased brake pipe pressure in cham-
ber 1 will be directly registered in the brake
pipe chamber 12 of the diaphragm structure
and the diaphragms will be moved down-
wardly and will carry the pilot valve to re-
lease position. In the release position of
115 this valve the equalizing chamber 55 will
be connected to atmosphere through cavity
61 in the pilot valve, passage 62, cavity 41
of the main slide valve and atmospheric
port 42. The pressure in chamber 55 will
not be completely exhausted to atmosphere
until the brake pipe pressure in chamber 12
has been raised to an equality with the un-
disturbed reservoir pressure in chamber 17.
120 The equalizing chamber 55 will be cut off
from communication with the brake cyl-
inder when cavity 64 has been moved out of
register with passage 52. If the communi-
cation between passages 51 and 52 were not
125

cut off and main slide valve did move to release position the operation would be as follows: The slow increase in brake pipe pressure such as does exist in a long train 5 when releasing the brakes, would operate the pilot valve to release position, and the brake cylinder pressure would be released through the diaphragm structure, at a rate proportional to the increase in brake pipe 10 pressure. But when the main slide valve is operated to release position to quickly exhaust the brake cylinder pressure, the pressure in the equalizing chamber 55 is also reduced at the same rate and the result 15 would be that because of the quick reduction of pressure in chamber 55 the pilot valve would operate to service position and feed brake pipe air into the brake cylinder in the same manner as it would when 20 maintaining brake cylinder leakage. With the communication closed between passages 25 51 and 52, the pilot valve operation is precisely as just described, but the brake pipe pressure entering passage 52 cannot flow to the brake cylinder through passage 51 because the cavity 64 has been moved out of 25 register with passage 52.

Service application when operating in graduated release.

30 The release governing valve is shifted to the left, as illustrated in Fig. 4 of the drawings, in order to adjust the triple valve for graduated release operations. This movement of the release governing valve closes the large atmospheric port 24 and closes the atmospheric port 29. This movement of the valve therefore closes communication between the retention chamber 25 and atmospheric port 29 and also communication between the brake cylinder exhaust port 21 and the atmospheric port 24. A cavity 60 in the release governing valve will connect together passages 58 and 59. Passage 58 35 leads direct to the brake cylinder passage 19. Passage 59 leads direct to passage 52. Passage 52 leads from the main slide valve seat direct to the brake cylinder pressure equalizing chamber 55. When, therefore, the 40 release governing valve is in graduated release position the equalizing chamber 55 is connected in all positions of the main slide valve, and independently of the main slide valve, with the brake cylinder passage 19. The service operation of the triple valve as a whole is precisely as described under the heading "Service position", the main slide valve in service position connecting the auxiliary reservoir to the brake cylinder and 45 the independent or supplementary valve 15 connecting the brake pipe to the brake cylinder. With the release governing valve in graduated release position the equalizing chamber 55 is connected to the brake cylinder through passage 52, passage 59, cavity 55

60 in the release governing valve, passage 58 to the brake cylinder passage 19 so that brake pipe air will flow to the brake cylinder independently of the main slide valve. 70

Graduated release.

The release operation, when operating in graduated release is wholly controlled by the independent pilot valve 15, the release movements of the main slide valve being 75 idle in graduated release operations.

When operating in graduated release, an increase in brake pipe pressure will operate the piston and main slide valve to release position as hereinbefore described, but the 80 brake cylinder pressure cannot be quickly released to atmosphere because the port 23 of the release governing valve is moved out of register with the atmospheric port 24. The purpose of connecting the passages 58 and 59 by the cavity 60 of the release governing valve is to permit the pilot valve to release brake cylinder pressure to atmosphere while the main slide valve is in release position, this being prevented when operating in quick release, as herein described. The flow of air from the brake cylinder to atmosphere will be, when operating in graduated release, as follows: Brake cylinder 85 pressure will flow through passages 19 and 58, cavity 60 of the release governing valve and passages 59 and 52, which lead direct to the equalizing chamber 55 between diaphragms 13 and 53, and from this chamber to the atmosphere through cavity 61 to the pilot valve passage 62, cavity 41 of the main slide valve, and the atmospheric port 42. 90

95 From the above description it will be understood that when operating in graduated release the brake cylinder is supplied with pressure both from the auxiliary reservoir and the brake pipe when a brake pipe reduction is made; but the discharge of pressure therefrom is controlled entirely by the pilot valve and the amount of pressure reduction is dependent upon the amount of increase in brake pipe pressure. 100

105 The release of brake cylinder pressure will be in direct proportion to the increase in brake pipe pressure registered in the brake pipe chamber 12. By increasing the pressure in chamber 12 a predetermined amount, for instance five pounds, the diaphragm structure will be moved downwardly and the pilot valve will be moved to release position. Brake cylinder pressure in chamber 55 will be released to atmosphere as hereinbefore described. When the pressure in chamber 55, and consequently in the brake cylinder, is reduced to such a degree that the undisturbed emergency reservoir pressure in chamber 17 will overcome the opposing pressures in the brake pipe chamber 12 and in the equalizing chamber 55 the diaphragms will be moved upwardly and the 115 120 125 130

pilot valve will be moved to lap position to prevent further escape of air from the chamber 55 and from the brake cylinder. If it be desired to still further reduce brake cylinder pressure a further increase in brake pipe pressure will be made and the release operation will be repeated. If it be desired to increase the brake cylinder pressure the brake pipe pressure will be reduced and the 10 pilot valve will move to application position and the main slide valve will also move to application position. In this manner the brake cylinder pressure may be increased or diminished by steps by decreasing or increasing the brake pipe pressure.

Automatic brake cylinder pressure retention means.

In operating trains equipped with the 20 present standard freight brake, such as the well known Westinghouse K type of triple valve, it is the usual practice to turn up pressure retainers when descending a grade. The purpose of the retainer is to hold a certain pressure in the brake cylinder while releasing the brakes and re-charging the auxiliary reservoir. When descending grades with the trains equipped with the ordinary standard freight brake of the Westinghouse 30 type it is the practice to apply the brakes to retard the speed of the train; to hold the brakes applied for a brief period, about thirty or forty seconds; to then release the brakes and re-charge the auxiliary reservoir, this release and recharging period being short, usually forty to sixty seconds; and then if the grade is long and heavy to again apply the brakes for a brief period and to again release them and re-charge the auxiliary reservoir. This operation is what is known as cycling and it is continued during the entire run down the grade. If the grade is heavy the application and holding and the release and re-charging operations follow each other rapidly and are of short duration. It is essential that the release and re-charge operations shall be as short as possible and be followed immediately by a re-application of the brakes in order to prevent 45 undue acceleration of the train on the grade.

The retainers are weighted or loaded valves which retain a certain portion of the brake cylinder pressure during the period of release and re-charge. These retainers have 55 what is called a certain "value," that is to say, they are constructed to retain a certain number of pounds pressure in the brake cylinder, and that fixes the value of the retainers. These values vary for different 60 grades. A retainer of light value will be used on trains running down low grades and a retainer of high value will be used on trains running down heavy grades. The heavy value retainers retain a heavier pres-

sure in the brake cylinders during the release and re-charging period.

The triple valve herein described provides means for automatically building up the brake cylinder pressure during cycling operations and avoids the use of the manually settable retainers.

The release governing valve in graduated release position, as shown in Fig. 4, prevents the exhaust of pressure from the retention chamber 25 through the atmospheric port 29. When the main slide valve is in release position the release cavity 20 thereof connects the brake cylinder passage 19 to the port 27^a leading into the retention chamber so that brake cylinder pressure will 80 flow into the retention chamber. A cavity 25^c of the main slide valve will connect the port and passage 25^b which leads from the retention chamber, to an atmospheric port 25^d. The chamber 25, as hereinbefore described is connected to the retention chamber 26 by passage 25^a. When the main slide valve is in release position the independent or pilot valve 15 will also be in release position and brake cylinder pressure will be 90 flowing through said valve to the atmospheric port 42. The ports 27^a and 25^b will be restricted ports, 25^b being more restricted than 27^a so that a certain predetermined proportion of the pressure flowing into 95 chamber 25 through the port 27^a will be retained therein and said pressure will be built up in the retention chamber 26. The amount of pressure built up in the chamber 26 will be dependent upon the length of 100 time the main slide valve remains in release position. During the entire time that the main slide valve remains in release position brake cylinder pressure will be flowing into chamber 25 through port 27^a and will be 105 flowing from said chamber to atmosphere through the port 25^b. This flow of air will not be interrupted when the independent valve 15 is moved to lap position. The pressure built up in the retention chamber 26 110 will oppose the brake cylinder pressure on the opposite side of the diaphragm 53 but will always be less than said pressure. When the brake pipe pressure is again reduced for another application of the brakes the main 115 slide valve will move to service position thereby cutting off further discharge of air from chamber 25 and interrupting the flow of air into said chamber. Thus the pressure built up in chambers 25 and 26 will 120 be retained therein and air will flow from the auxiliary reservoir to the brake cylinder as hereinbefore described. The reduction of brake pipe pressure in chamber 12 will result in the independent or pilot valve moving 125 to service position to connect the brake pipe to the brake cylinder. The independent valve will remain in service position until the

brake cylinder pressure built up in chamber 55 will be sufficient, with the brake pipe pressure in chamber 12, to overcome the pressure in the retention chamber 26 and the emergency reservoir pressure in chamber 17. Because of the pressure retained in chamber 26 the pressure built up in the equalizing chamber 55 must be greater than would have been necessary with no pressure in the retention chamber. The result will be that a higher brake cylinder pressure will be built up and this degree of pressure will be dependent upon the amount of pressure trapped in the retention chamber. As hereinbefore stated the amount of pressure trapped in the retention chamber will be dependent upon the length of time the main slide valve remains in release position, the shorter the period of release the higher will be the pressure in chamber 26 and the longer the period of release the lower the trapped pressure will be. It is therefore clear that in cycling operations the brake cylinder pressure will be built up in accordance with the rapidity of the braking cycles. On heavy grades the cycling will be rapid and the periods of release will be short while on low grades cycling operations will be slower and the periods of release will be longer. The result will be that when cycling on heavy grades there will be a greater build up of brake cylinder pressure than there will be when cycling on low grades. It is also manifest that by holding the main slide valve in release position for a sufficient time the entire brake cylinder pressure will be released. In these release operations the main slide valve is idle except that it connects the small blow down or leak port 25^b to atmosphere. The amount of brake cylinder pressure escaping through said port 25^b will be small as compared with the amount of brake cylinder pressure exhausted through the independent pilot valve and the atmospheric port 42.

When the release governing valve is in quick release position chamber 25 is open to atmosphere through the atmospheric port 29 and there will be no appreciable build up or accumulation of pressure in chambers 25 and 26 when the main slide valve is moved to release position.

Emergency position.

The brake pipe pressure is reduced in the usual manner at an emergency rate for an emergency application of the brakes. This emergency reduction in chamber 1 will be sufficient to permit the auxiliary reservoir pressure in chamber 5 to move the main piston 44 to the extreme limit of its movement toward the left against the tension of the graduating spring 48. This movement of the piston and the piston stem will carry the main slide valve to emergency posi-

tion as shown in Fig. 3. With the main slide valve in emergency position the chamber 30^b will be vented to atmosphere through passage 32, cavity 41 of the main slide valve and atmospheric port 42. Auxiliary reservoir pressure in chamber 9 will thereupon force the piston 30 inwardly to the position shown in Fig. 3 and the lever 30^a will unseat the check valve 10 and permit the emergency reservoir air to flow direct to the chamber 5 through chamber 9 and passage 8. Air from the auxiliary reservoir and the emergency reservoir will flow direct to the brake cylinder through the emergency port 63 of the main slide valve 80 and brake cylinder passage 19.

The brake pipe vent valve is opened to effect a rapid and positive serial emergency action throughout the train. When the main slide valve is in emergency position the chamber 36^a above the vent valve piston 33 is vented into the chamber 39 through passage 38, cavity 65 in the main slide valve, port and passage 40 which leads to the chamber 39. Chamber 39 is at atmospheric pressure in all positions of the main slide valve except emergency position. When the chamber 36^a is vented, as described, the brake pipe pressure below the piston 33 will raise said piston and open the brake pipe vent valve 34, thereby permitting brake pipe pressure to flow directly to atmosphere. When the brake pipe pressure has been reduced sufficiently to bring about approximately an equalization between the pressure above and below the piston 33 the valve 34 will be closed by the spring 66 and the air velocity past the valve. The emergency operation of the triple valve, whether operated in graduated release or in quick release, is precisely as described, except that when operating in graduated release any pressure existing in the retention chamber at the time of the emergency operation will be held or trapped therein. Pressure in all of the other chambers of the triple valve will be equalized. As shown in Fig. 3 air will flow from chamber 5 into chamber 12 through passage 11 when the main piston 44 is in emergency position so that the pressures in chambers 12, 55 and 17 will be equalized. Air will leak through the port 37 to more quickly bring about an equalization of pressures on opposite sides of the piston 33.

Release of the brakes after an emergency application.

The release of the brakes after an emergency application is obtained by increasing the brake pipe pressure above the brake cylinder pressure existing in chamber 5 at the right side of piston 44. The parts will then assume release position and the system will again be charged as described. Should the

release governing valve be in graduated release position, the release of the brake cylinder pressure will be controlled entirely by the pilot valve and will be reduced at a slow rate, whereas should this valve be in quick release position, the brake cylinder pressure will be quickly released through the main slide valve and release governing valve. The rising brake pipe pressure in chamber 36 will leak through the port 37 in order to maintain an equalization of pressures on opposite sides of the piston 33.

What I claim:

1. An air brake apparatus comprising an emergency reservoir, an auxiliary reservoir, a brake pipe, a brake cylinder, means subject to brake pipe pressure and auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, and means operated by emergency reservoir pressure upon a reduction of brake pipe pressure to place the brake pipe in communication with the brake cylinder, said means closing said communication when the combined brake cylinder pressure and reduced brake pipe pressure dominates the emergency reservoir pressure and thereafter controlling the degree of pressure retained in the brake cylinder.
2. An air brake apparatus comprising an emergency reservoir, an auxiliary reservoir, a brake pipe, a brake cylinder, means subject to brake pipe pressure and auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, and means operated by emergency reservoir pressure upon a reduction of brake pipe pressure to place the brake pipe in communication with the brake cylinder, said means closing said communication when the combined brake cylinder pressure and reduced brake pipe pressure dominates the emergency reservoir pressure.
3. An air brake apparatus comprising an emergency reservoir, an auxiliary reservoir,

a brake cylinder, a brake pipe, and two valve devices operated by a reduction of brake pipe pressure, one of said valve devices closing communication between brake pipe and auxiliary reservoir and placing the auxiliary reservoir in communication with the brake cylinder and closing said brake cylinder communication upon an equalization of brake pipe and auxiliary reservoir pressures, whereby a certain volume of air will be discharged from the auxiliary reservoir into the brake cylinder for a given brake pipe reduction, the other valve device placing the brake pipe in communication with the brake cylinder and closing said communication when a predetermined brake cylinder pressure is secured from auxiliary reservoir and brake pipe.

4. An air brake apparatus comprising an emergency reservoir, an auxiliary reservoir, a brake cylinder, a brake pipe, and two valve devices operated by a reduction of brake pipe pressure, one closing communication between brake pipe and auxiliary reservoir and placing the auxiliary reservoir in communication with the brake cylinder and closing said brake cylinder communication upon an equalization of brake pipe and auxiliary reservoir pressures, whereby a certain volume of air will be discharged from the auxiliary reservoir into the brake cylinder for a given brake pipe reduction, the other valve device placing the brake pipe in communication with the brake cylinder and closing said communication when a predetermined brake cylinder pressure is secured from the auxiliary reservoir and brake pipe, said other valve device being controlled by brake pipe, brake cylinder and emergency reservoir pressures.

5. An air brake apparatus comprising an emergency reservoir, an auxiliary reservoir, a brake cylinder, a brake pipe, a main valve device and a secondary valve device both of said devices being operated by a reduction of brake pipe pressure, the main valve device closing communication between the brake pipe and auxiliary reservoir and placing the auxiliary reservoir in communication with the brake cylinder and closing said brake cylinder communication upon an equalization of brake pipe and auxiliary reservoir pressures, whereby a certain volume of air will be discharged from the auxiliary reservoir into the brake cylinder for a given brake pipe reduction, said main valve device also operating upon a sudden reduction of brake pipe pressure to place the emergency reservoir and auxiliary reservoir in communication with the brake cylinder for an emergency application of the brakes, the secondary valve device placing the brake pipe in communication with the brake cylinder and closing said communication when a predetermined brake cylinder pressure.

pressure is secured from auxiliary reservoir and brake pipe, said secondary valve device being controlled by brake pipe, brake cylinder and emergency reservoir pressures.

- 5 6. A triple valve for air brake apparatus comprising a main slide valve, a graduating valve, a piston connected to said valves and subject on one side to brake pipe pressure and on its other side to auxiliary reservoir pressure and operating upon an increase of 70
10 brake pipe pressure to move said valves to release position to connect the brake cylinder to a main exhaust port and to open communication from the brake pipe to auxiliary reservoir and operating upon a reduction of 75
15 brake pipe pressure to move said valves to application position to connect the auxiliary reservoir to the brake cylinder and to close communication from the brake pipe 20 to auxiliary reservoir, said communication with the brake cylinder being closed upon an equalization of pressures in the brake pipe and in the auxiliary reservoir whereby a certain volume of air will be discharged 25
25 from the auxiliary reservoir to the brake cylinder for a given brake pipe reduction, a secondary or pilot valve subject to brake pipe, brake cylinder and emergency reservoir pressures and operating upon a reduction 30
30 in brake pipe pressure to connect the brake pipe to the brake cylinder and operating upon an increase in brake pipe pressure to connect the brake cylinder to atmosphere through a secondary exhaust port, a release 35
35 governing valve having a quick release position and a graduated release position, said valve in quick release position opening the main brake cylinder exhaust port to atmosphere and in its graduated release position closing said main exhaust port and opening communication between the brake cylinder and the secondary exhaust port through the pilot valve whereby the pilot valve will 40
40 control the exhaust of brake cylinder pressure when the release governing valve is in graduated release position, and means whereby the main slide valve will control brake cylinder exhaust through the pilot valve and the secondary exhaust port. 45
50 7. An air brake apparatus comprising an emergency reservoir, an auxiliary reservoir, a brake pipe, a brake cylinder, main valve means subject to brake pipe pressure and auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, said main valve means operating upon an increase of brake pipe pressure to connect the brake cylinder to a main exhaust port, a secondary valve means operating upon a reduction of brake pipe pressure to place 125
60 65 120
65 130

and a secondary or pilot valve operating upon a reduction of brake pipe pressure to admit brake pipe air only to the brake cylinder until a predetermined pressure is built up in said brake cylinder from the auxiliary 70
75 reservoir and brake pipe, whereby the movement of the said main valve means will be made certain by the local reduction of brake pipe pressure and the predetermined pressure in the brake cylinder will be maintained 75
80 regardless of brake cylinder leaks and variations in brake cylinder piston travel.

8. An air brake apparatus comprising an emergency reservoir, an auxiliary reservoir, a brake pipe, a brake cylinder, main valve 80
85 means subject to brake pipe pressure and auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressure in the brake pipe and in the auxiliary reservoir whereby a certain volume of air will be discharged 90
95 from the auxiliary reservoir to the brake cylinder for a given brake pipe reduction, said main valve means operating upon an increase of brake pipe pressure to connect the brake cylinder to a main exhaust port, means operating upon an increase of brake pipe pressure to slowly release brake cylinder pressure through a secondary exhaust port and independent of the main exhaust 100
105 port of the main valve means and at a uniform rate without regard to the degree of increased brake pipe pressure, and manually operable means in one position rendering the main exhaust means ineffective and the secondary exhaust means effective and in an another position rendering the main exhaust means effective and the secondary exhaust means ineffective.

9. An air brake apparatus comprising an 110
115 emergency reservoir, an auxiliary reservoir, a brake pipe, a brake cylinder, main valve means subject to brake pipe pressure and auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressure in the brake pipe and in the auxiliary reservoir whereby a certain volume of air will be discharged from the auxiliary reservoir to the brake cylinder for a given brake pipe reduction, said main valve means operating upon an increase of brake pipe pressure to connect the brake cylinder to a main exhaust port, a secondary valve means operating upon a reduction of brake pipe pressure to place 125
120
130

the brake pipe in communication with the brake cylinder and close said communication when a predetermined brake cylinder pressure is secured from the auxiliary reservoir and brake pipe, and operating upon an increase of brake pipe pressure to slowly release brake cylinder pressure to a secondary exhaust port and independent of the main exhaust port of the main valve means, 5
10 said secondary valve means being controlled by brake pipe, brake cylinder and emergency reservoir pressures, and manually operable means in one position rendering the main exhaust means ineffective and the 15 secondary exhaust means effective and in another position rendering the main exhaust means effective and the secondary exhaust means ineffective.

10. An air brake apparatus comprising an 20 emergency reservoir, an auxiliary reservoir, a brake pipe, a brake cylinder, main valve, means subject to brake pipe pressure and auxiliary reservoir pressure and operating upon a reduction in brake pipe pressure to 25 open communication between the auxiliary reservoir and the brake cylinder and to close communication between the brake pipe and auxiliary reservoir, said communication with the brake cylinder being closed upon an 30 equalization of pressure in the brake pipe and in the auxiliary reservoir whereby at certain volume of air will be discharged from the auxiliary reservoir to the brake cylinder for a given brake pipe reduction, said main valve means operating upon an 35 increase of brake pipe pressure to connect the brake cylinder to a main exhaust port, a secondary independent valve operating upon a reduction in brake pipe pressure to connect the brake pipe to the brake cylinder and to close said communication when a 40 predetermined brake cylinder pressure is secured from the auxiliary reservoir and the brake pipe and operating upon an increase 45 of brake pipe pressure to release position to connect the brake cylinder to atmosphere through a secondary exhaust port, means controlled by brake pipe and brake cylinder pressures opposed to the pressure of an 50 emergency reservoir for actuating said independent valve, and means whereby said pressure controlling valve will maintain the brake cylinder pressure in direct proportion to the brake pipe reduction the brake 55 cylinder pressure moving said independent valve to release position when said pressure exceeds the desired brake cylinder pressure, and emergency reservoir pressure moving said valve to application position when the 60 brake cylinder pressure is below the desired brake cylinder pressure.

11. A triple valve for air brake apparatus comprising a main slide valve, a graduating valve, a piston connected to said valves and subject on one side to brake pipe pressure

and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a secondary independent valve controlling a restricted secondary exhaust port adapted to 85 slowly release brake cylinder pressure upon an increase in brake pipe pressure for a release of the brakes, and means controlled by brake pipe and brake cylinder pressures opposed to the pressure of an emergency reservoir for actuating said independent valve.

12. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, and a secondary independent valve operating upon a decrease in brake pipe pressure to connect the brake pipe alone to the brake cylinder through a cavity in the main valve when said slide valve is in service application position.

13. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduc-

tion of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a secondary independent valve operating upon a decrease in brake pipe pressure to connect the brake pipe alone to the brake cylinder through a cavity in the main slide valve when said slide valve is in service application position, and means controlled by brake pipe and brake cylinder pressures opposed to the pressure of an emergency reservoir for actuating said independent valve.

14. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a quick release valve controlling a main exhaust through the main slide valve and adapted to be manually operated to render the main exhaust ineffective in release operations, and a secondary independent valve operating upon a decrease in brake pipe pressure to connect the brake pipe to the brake cylinder and operating upon an increase in brake pipe pressure to release position to connect the brake cylinder to atmosphere through a secondary restricted port.

15. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating

upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a quick release valve controlling a main exhaust through the main slide valve and adapted to be manually operated to render the main exhaust through the slide valve ineffective in release operations, a secondary independent valve operating upon a decrease in brake pipe pressure to connect the brake pipe to the brake cylinder and operating upon an increase in brake pipe pressure to release position to connect the brake cylinder to atmosphere through a secondary port, and means controlled by brake pipe and brake cylinder pressures opposed to the pressure of an emergency reservoir for actuating said independent valve.

16. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a quick release valve controlling a main exhaust through the main slide valve and adapted to be manually operated to render the main exhaust through the main slide valve ineffective in release operations, a secondary independent valve operating upon a decrease in brake pipe pressure to connect the brake pipe to the brake cylinder and operating upon an increase in brake pipe pressure to release position to connect the brake cylinder to atmosphere through a secondary port, means controlled by brake pipe and brake cylinder pressures opposed to the pressure of an emergency reservoir for actuating said independent valve, and

means whereby said pressure controlling valve will maintain the brake cylinder pressure in direct proportion to the brake pipe reduction.

- 5 17. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe 10 to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a quick release valve controlling a main exhaust through the main slide valve and adapted to be manually operated 15 to render the main exhaust through the main slide valve ineffective in release operations, a secondary independent valve operating upon a decrease in brake pipe pressure to connect the brake pipe to the brake cylinder and operating upon an increase in brake pipe pressure to release position to connect the brake cylinder to atmosphere through a secondary exhaust port, means controlled by brake pipe and brake cylinder pressures opposed to the pressure of an emergency reservoir for actuating said independent valve, and means whereby said pressure controlling valve will maintain the brake cylinder pressure in direct proportion to the brake pipe reduction the brake cylinder pressure moving said independent valve to release position when said pressure exceeds the desired brake cylinder pressure, and emergency reservoir pressure moving said valve to application position when the brake cylinder pressure is below the desired brake cylinder pressure. 20

18. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir and operating upon a reduction of brake pipe pressure to move said valves to application position to 25

ing closed upon an equalization of pressures in the brake pipe and in the auxiliary reservoir whereby a certain volume of air will be discharged from the auxiliary reservoir to the brake cylinder for a given brake pipe reduction, a secondary independent brake cylinder pressure controlling valve adapted in service position to connect the brake pipe to the brake cylinder through a cavity in the main slide valve when said slide valve is in service application position, and means controlled by brake pipe and brake cylinder pressures opposed to the pressure of an emergency reservoir for actuating said independent pressure controlling valve. 19. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir whereby a certain volume of air will be discharged from the auxiliary reservoir to the brake cylinder for a given brake pipe reduction, a secondary independent valve operating upon a decrease in brake pipe pressure to connect the brake pipe to the brake cylinder and operating upon an increase in brake pipe pressure to release position to connect the brake cylinder to atmosphere through a secondary port, means controlled by brake pipe and brake cylinder pressures opposed to the pressure of an emergency reservoir for actuating said independent valve, and means whereby said pressure controlling valve will maintain the brake cylinder pressure in direct proportion to the brake pipe reduction the brake cylinder pressure moving said independent valve to release position when said pressure exceeds the desired brake cylinder pressure, and emergency reservoir pressure moving said valve to application position when the brake cylinder pressure is below the desired brake cylinder pressure. 20. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to a release position and operating upon a reduction of brake pipe pressure to move said valve to application position to connect the auxiliary

- reservoir to the brake cylinder, in combination with means operated by reductions of and increases in brake pipe pressure to build up the brake cylinder pressure.
21. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, in combination with a pilot valve subject to brake pipe, brake cylinder and emergency reservoir pressures, the brake cylinder pressure moving said pilot valve to lap position, and means whereby the brake cylinder pressure will be built up by cycling operations.
22. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with automatically operating means to build up brake cylinder pressure by cycling operations, the extent of the build-up of brake cylinder pressure depending upon the rapidity of the cycling operations.
23. A triple valve for air brake apparatus comprising a main slide valve, a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with a pilot valve and means whereby the main slide valve will build up brake cylinder pressure by cycling operations, the extent of the build-up of brake cylinder pressure depending upon the rapidity of the cycling operations, and a release governing valve having a graduated release position and a quick release position, said valve in its quick release position preventing the build up of brake cylinder pressure and in its graduated release position permitting the said build up of brake cylinder pressure.
24. A triple valve for air brake apparatus comprising a main slide valve, a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with a pilot valve, a retention chamber, the main slide valve in release position connecting the brake cylinder to the retention chamber and the retention chamber to atmosphere through a restricted port.
25. A triple valve for air brake apparatus comprising a main slide valve, a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with a brake cylinder pressure control chamber, a pilot valve, a retention chamber, means operating upon a reduction of brake pipe pressure to move the pilot valve to application position to admit air into the brake cylinder pressure control chamber and to the brake cylinder, said means operating upon an increase in brake pipe pressure to move the pilot valve to release position to connect the control chamber to atmosphere, and means to move said pilot valve to lap position to close communication between the control chamber and the brake cylinder, the main slide valve in release position connecting the brake cylinder to the retention chamber and the retention chamber to atmosphere through a restricted port.
26. A triple valve for air brake apparatus comprising a main slide valve, a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, a retention chamber, the main slide valve in release position connecting the brake cylinder to the retention chamber and to atmosphere, the said main valve in service position closing communication between the brake cylinder and the retention chamber and the retention chamber and atmosphere.
27. A triple valve for air brake apparatus comprising a main slide valve, a piston con-

5 nected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and means whereby 10 the main slide valve will automatically build up brake cylinder pressure by cycling operations, the extent of the build-up of brake cylinder pressure depending upon the rapidity of the cycling operations.

15 28. A triple valve for air brake apparatus comprising a main slide valve, a piston connected to said valve and subject on one side to brake pipe pressure and on its other side to auxiliary reservoir pressure and operating 20 upon an increase of brake pipe pressure to move the main valve to release position and operating upon a reduction of brake pipe pressure to move said valve to application position to connect the auxiliary reservoir to the brake cylinder, and means whereby 25 the main slide valve will automatically build up brake cylinder pressure by cycling operations.

30 29. An air brake apparatus comprising an emergency reservoir, an auxiliary reservoir, a brake cylinder, a brake pipe, a main valve device and a secondary valve device both of said devices being operated by a reduction of brake pipe pressure, the main valve device 35 closing communication between brake pipe and auxiliary reservoir and placing the auxiliary reservoir in communication with the brake cylinder and closing said brake cylinder communication upon an equalization of 40 brake pipe and auxiliary reservoir pressures, whereby a certain volume of air will be discharged from the auxiliary reservoir into the brake cylinder for a given brake pipe reduction, said main valve device also operating 45 upon a sudden reduction of brake pipe pressure to place the emergency reservoir and auxiliary reservoir in communication with the brake cylinder for an emergency application of the brakes, the secondary 50 valve device placing the brake pipe in communication with the brake cylinder and closing said communication when a predetermined brake cylinder pressure is secured from auxiliary reservoir and brake pipe, 55 said secondary valve device being controlled by brake pipe, brake cylinder and emergency reservoir pressures, and means whereby the main slide valve in service position will connect the brake cylinder to the brake pipe 60 through the secondary valve and will connect the brake cylinder to atmosphere through passages controlled by the secondary valve.

65 30. An air brake apparatus comprising an emergency reservoir, an auxiliary reservoir,

a brake cylinder, a brake pipe, a main valve device and a secondary valve device both of said devices being operated by a reduction of brake pipe pressure, the main valve device closing communication between brake 70 pipe and auxiliary reservoir and placing the auxiliary reservoir in communication with the brake cylinder and closing said brake cylinder communication upon an equalization of brake pipe and auxiliary reservoir 75 pressures, whereby a certain volume of air will be discharged from the auxiliary reservoir into the brake cylinder for a given brake pipe reduction, said main valve device also operating upon a sudden reduction of brake 80 pipe pressure to place the emergency reservoir and auxiliary reservoir in communication with the brake cylinder for an emergency application of the brakes, the secondary 85 valve device placing the brake pipe in communication with the brake cylinder and closing said communication when a predetermined brake cylinder pressure is secured from auxiliary reservoir and brake pipe, said secondary valve device being controlled 90 by brake pipe, brake cylinder and emergency reservoir pressures, means whereby the main slide valve in service position will connect the brake cylinder to the brake pipe and will connect the brake cylinder to atmosphere 95 through passages controlled by the independent valve, and means whereby the main slide valve in emergency position will close the passages controlled by the independent valve.

31. An air brake apparatus comprising an emergency reservoir, an auxiliary reservoir, a brake cylinder, a brake pipe, a main valve device and a secondary valve device, both of said devices being operated by a reduction of brake pipe pressure, the main valve device closing communication between brake pipe and auxiliary reservoir and placing the auxiliary reservoir in communication with the brake cylinder and closing said brake 100 cylinder communication upon an equalization of brake pipe and auxiliary reservoir pressures, whereby a certain volume of air will be discharged from the auxiliary reservoir into the brake cylinder for a given brake pipe reduction, the secondary valve device placing the brake pipe in communication with the brake cylinder and closing said communication when a predetermined brake cylinder pressure is secured from auxiliary 105 reservoir and brake pipe, said secondary valve device being controlled by brake pipe, brake cylinder and emergency reservoir pressures, and means whereby the main slide valve in emergency position will render the secondary valve device ineffective. 110

32. A triple valve for air brake apparatus comprising a main slide valve, a graduating valve, a piston connected to said valves and subject on one side to brake pipe pressure and on its other side to auxiliary reservoir 115

pressure and operating upon an increase of 65
brake pipe pressure to move the said valves
to release position to connect the brake cylinder
to a main exhaust port and to open communication
5 to the brake pipe to auxiliary reservoir, and operating upon a reduction of
brake pipe pressure to move said valves to
application position to connect the auxiliary reservoir
to the brake cylinder and to close
10 communication from the brake pipe to auxiliary reservoir, said communication with
the brake cylinder being closed upon an
equalization of pressures in the brake pipe
and in the auxiliary reservoir whereby a cer-
tain volume of air will be discharged from
15 the auxiliary reservoir to the brake cylinder
for a given brake pipe reduction, a sec-
ondary or pilot valve subject to brake pipe,
brake cylinder and emergency reservoir
pressures and operating upon a reduction in
20 brake pipe pressure to connect the brake pipe
to the brake cylinder and operating upon an increase in brake pipe pressure to
connect the brake cylinder to atmosphere
through a secondary exhaust port, and
means whereby the main slide valve in emer-
25 gency position will render the secondary
valve device ineffective.

33. An air brake apparatus comprising an
30 emergency reservoir, an auxiliary reservoir,
a brake pipe, a brake cylinder, main valve means
subject to brake pipe pressure and auxiliary reservoir pressure
and operating upon a reduction in brake
35 pipe pressure to open communication be-
tween the auxiliary reservoir and the
brake cylinder and to close communication
between the brake pipe and auxiliary reservoir,
said communication with the
40 brake cylinder being closed upon an equalization
of pressures in the brake pipe and
in the auxiliary reservoir whereby a certain
volume of air will be discharged from
the auxiliary reservoir to the brake cylinder
45 for a given brake pipe reduction, a sec-
ondary or pilot valve operating upon a re-
duction of brake pipe pressure to admit
brake pipe air only to the brake cylinder
until a predetermined pressure is built up
50 in said brake cylinder from the auxiliary
reservoir and brake pipe, whereby the move-
ment of the said main valve means will be
made certain by the local reduction of brake
pipe pressure and the predetermined pres-
55 sure in the brake cylinder will be maintained
regardless of brake cylinder leaks and varia-
tions in brake cylinder piston travel, means
whereby the auxiliary reservoir pressure will
hold the emergency reservoir sealed in the
60 service position of the main valve means,
and means whereby the main valve in emer-
gency position will permit auxiliary reser-
voir pressure to open communication be-
tween emergency reservoir and the auxiliary

reservoir for an emergency application of
the brakes.

34. A triple valve for air brake apparatus
comprising a main slide valve, a graduating
70 valve, a piston connected to said valves and
subject on one side to brake pipe pressure
and on its other side to auxiliary reservoir
pressure and operating upon an increase of
brake pipe pressure to move the said valves
75 to release position to connect the brake cylinder
to a main exhaust port and to open communication
from the brake pipe to auxiliary reservoir,
and operating upon a reduction of
brake pipe pressure to move said valves
80 to application position to connect the auxiliary reservoir to the brake cylinder and
to close communication from the brake pipe
to auxiliary reservoir, said communication
with the brake cylinder being closed upon an
equalization of pressures in the brake pipe
85 and in the auxiliary reservoir whereby a cer-
tain volume of air will be discharged from
the auxiliary reservoir to the brake cylinder
for a given brake pipe reduction, and
provided with a pilot valve and means
90 whereby the main slide valve will build up
brake cylinder pressure by cycling operations,
the extent of the build-up of brake cylinder
pressure depending upon the rapidity
of the cycling operations, and a release gov-
95 erning valve having a graduated release pos-
ition and a quick release position, said valve
in its quick release position preventing the
build up of brake cylinder pressure and in
its graduated release position permitting the
100 said build up of brake cylinder pressure.

35. An air brake apparatus comprising an
emergency reservoir, an auxiliary reservoir,
a brake cylinder, a brake pipe, a main valve
device, a pilot valve device, means whereby
the main valve device will operate upon a re-
duction of brake pipe pressure to connect
105 the auxiliary reservoir to the brake cylinder
and then close said communication upon a
substantial equalization of brake pipe and
auxiliary reservoir pressures, means whereby
the pilot valve will move to application pos-
110 sition and connect the brake pipe to the brake
cylinder upon a reduction of brake pipe
pressure, means whereby the pilot valve will
maintain the brake cylinder pressure at a
predetermined ratio to the brake pipe re-
duction, said pilot valve moving to release
115 position when the brake cylinder pressure
exceeds the predetermined ratio to the brake
pipe reduction and moving to application
position when the brake cylinder pressure
is below the predetermined ratio to the brake
pipe reduction, and means whereby the main
120 and pilot valves will be moved to release
position upon an increase of brake pipe pres-
sure.

36. An air brake apparatus comprising an
emergency reservoir, an auxiliary reservoir,

a brake pipe, a brake cylinder, main valve means subject to brake pipe pressure and auxiliary reservoir pressure and operating upon a reduction in brake pipe pressure to 5 open communication between the auxiliary reservoir and the brake cylinder and to close communication between the brake pipe and auxiliary reservoir; said communication with the brake cylinder being closed upon 10 an equalization of pressure in the brake pipe and in the auxiliary reservoir whereby a certain volume of air will be discharged from the auxiliary reservoir to the brake cylinder for a given brake pipe reduction, 15 said main valve means operating upon an increase of brake pipe pressure to connect the brake cylinder to a main exhaust port, a secondary valve means operating upon a reduction of brake pipe pressure to place 20 the brake pipe in communication with the brake cylinder and close said communication when a predetermined brake cylinder pressure is secured from the auxiliary reservoir and brake pipe, and operating upon an in- 25 crease of brake pipe pressure to slowly release brake cylinder pressure to a secondary exhaust port and independent of the main exhaust port of the main valve means, said secondary valve means being controlled by 30 brake pipe, brake cylinder and emergency reservoir pressures, manually operable means in one position rendering the main exhaust means ineffective and the secondary exhaust means effective and in another position 35 rendering the main exhaust means effective and the secondary exhaust means ineffective, and means whereby said secondary valve will in all positions of the said manually operable means establish and maintain 40 the brake cylinder pressure in direct proportion to a given brake pipe pressure reduction and will, when the main exhaust is ineffective, reduce and maintain brake cylinder pressure in direct proportion to a given 45 increase in brake pipe pressure.

37. An air brake apparatus comprising an emergency reservoir; an auxiliary reservoir; a brake pipe; a brake cylinder; means subject to brake pipe pressure and auxiliary reservoir pressure and operating upon a reduction in brake pipe pressure to open 50 communication between the auxiliary reservoir and the brake cylinder and to close communication between the brake pipe and auxiliary reservoir, said communication with the brake cylinder being closed upon an equalization of pressures in the brake pipe and in the auxiliary reservoir, whereby a certain volume of air will be discharged 55 from the auxiliary reservoir to the brake cylinder for a given brake pipe reduction; and means operated by emergency reservoir pressure upon a reduction of brake pipe pressure to place a pressure supply in communication with the brake cylinder, said 60 from the auxiliary reservoir to the brake cylinder for a given brake pipe reduction; and means operated by emergency reservoir pressure upon a reduction of brake pipe pressure to place a pressure supply in communication with the brake cylinder, said 65

means closing said communication when the combined brake cylinder pressure and reduced brake pipe pressure dominates the emergency reservoir pressure, and thereafter controlling the degree of pressure retained 70 in the brake cylinder.

38. An air brake apparatus comprising an emergency reservoir; an auxiliary reservoir; a brake pipe; a brake cylinder; means subject to brake pipe pressure and auxiliary reservoir pressure and operating upon a reduction in brake pipe pressure to open communication between the auxiliary reservoir and the brake cylinder and the close communication between the brake pipe and auxiliary reservoir, said communication with the brake cylinder being closed upon an equalization of pressures in the brake pipe and in the auxiliary reservoir, whereby a certain volume of air will be discharged 80 from the auxiliary reservoir to the brake cylinder for a given brake pipe reduction; and means operated by emergency reservoir pressure upon a reduction of brake pipe pressure to place a pressure supply in communication with the brake cylinder, said means closing said communication when the combined brake cylinder pressure and reduced brake pipe pressure dominates the 85 emergency reservoir pressure.

39. An air brake apparatus comprising an emergency reservoir; an auxiliary reservoir; a brake cylinder; a brake pipe; and two valve devices operated by a reduction of brake pipe pressure, one of said valve devices closing communication between the brake pipe and the auxiliary reservoir and placing the auxiliary reservoir in communication with the brake cylinder and closing said brake cylinder communication upon an equalization of brake pipe and auxiliary reservoir pressures, whereby a certain volume of air will be discharged from the auxiliary reservoir into the brake cylinder for a given brake pipe reduction, the other valve 100 device placing a secondary pressure supply in communication with the brake cylinder and closing said communication when a predetermined brake cylinder pressure is secured from the auxiliary reservoir and the 105 secondary pressure supply.

40. An air brake apparatus comprising an emergency reservoir; an auxiliary reservoir; a brake cylinder; a brake pipe; and two valve devices operated by a reduction of brake pipe pressure, one closing communication between brake pipe and auxiliary reservoir and placing the auxiliary reservoir in communication with the brake cylinder and closing said brake cylinder communication upon an equalization of brake pipe and auxiliary reservoir pressures, whereby a certain volume of air will be discharged from the auxiliary reservoir into the brake cylinder for a given brake pipe reduction, the other 115

valve device placing a secondary pressure supply in communication with the brake cylinder and closing said communication when a predetermined brake cylinder pressure is secured from the auxiliary reservoir and the secondary pressure supply, said other valve device being controlled by brake pipe, brake cylinder and emergency reservoir pressures.

41. A triple valve for air brake apparatus comprising a main slide valve; a graduating valve; a piston connected to said valves and subject on one side to brake pipe pressure and on its other side to auxiliary reservoir pressure and operating upon an increase of 10 brake pipe pressure to move the said valves to release position to connect the brake cylinder to a main exhaust port and to open communication from the brake pipe to auxiliary reservoir, and operating upon a reduction 15 of brake pipe pressure to move said valves to application position to connect the auxiliary reservoir to the brake cylinder and to close communication from the brake pipe to auxiliary reservoir, said communication 20 with the brake cylinder being closed upon an equalization of pressures in the brake pipe and in the auxiliary reservoir whereby a certain volume of air will be discharged 25 from the auxiliary reservoir to the brake cylinder for a given brake pipe reduction; a secondary independent valve controlling a restricted exhaust and adapted to slowly release brake cylinder pressure upon an increase in brake pipe pressure for a release 30 of the brakes; and means controlled by brake pipe and brake cylinder pressures opposed to the pressure of an emergency reservoir for actuating said independent valve.

42. A triple valve for air brake apparatus comprising a main slide valve; a graduating valve; a piston connected to said valves and subject on one side to brake pipe pressure and on its other side to auxiliary reservoir pressure and operating upon an increase of 40 brake pipe pressure to move the said valves to release position to connect the brake cylinder to a main exhaust port and to open communication from the brake pipe to auxiliary reservoir, and operating upon a reduction 45 of brake pipe pressure to move said valves to application position to connect the auxiliary reservoir to the brake cylinder and to close communication from the brake pipe to auxiliary reservoir, said communication 50 with the brake cylinder being closed upon an equalization of pressures in the brake pipe and in the auxiliary reservoir whereby a certain volume of air will be discharged 55 from the auxiliary reservoir to the brake cylinder for a given brake pipe reduction; a secondary independent valve controlling a restricted exhaust and adapted to slowly release brake cylinder pressure upon an increase of 60 brake pipe pressure for a release 65 of the brakes; means controlled by

brake pipe and brake cylinder pressures opposed to the pressure of an emergency reservoir for actuating said independent valve; a manually operable release-governing valve; means whereby the release-governing valve 70 in one position will render the main slide valve controlling in release operations and in another position will render the secondary independent valve controlling in release operations; and means whereby when the 75 secondary valve is controlling in release operations the brake cylinder pressure will be released in direct ratio to the increase in brake pipe pressure.

43. An air brake apparatus comprising an 80 emergency reservoir; an auxiliary reservoir; a brake cylinder; a brake pipe; a main valve device; a secondary valve device; means whereby the main valve device will operate upon a reduction of brake pipe pressure to 85 connect the auxiliary reservoir to the brake cylinder and then close said communication upon a substantial equalization of brake pipe and auxiliary reservoir pressures; means whereby the secondary valve will move to 90 application position and connect a pressure supply independent of the auxiliary reservoir to the brake cylinder upon a reduction of brake pipe pressure; means whereby the secondary valve will maintain the brake cylinder 95 pressure at a predetermined ratio to the brake pipe reduction, said secondary valve moving to release position when the brake cylinder pressure exceeds the predetermined ratio to the brake pipe reduction and moving 100 to application position when the brake cylinder pressure is below the predetermined ratio to the brake pipe reduction; and means whereby the main and secondary valves will be moved to release position upon an increase of 105 brake pipe pressure.

44. An air brake apparatus comprising a single brake pipe; an emergency reservoir; an auxiliary reservoir; means to charge both said reservoirs upon an increase of pressure 110 in the said brake pipe; a brake cylinder; a main valve device; a secondary valve device; means whereby the main valve device will operate upon a reduction of brake pipe pressure to connect the auxiliary reservoir to 115 the brake cylinder and then close said communication upon a substantial equalization of brake pipe and auxiliary reservoir pressures; means whereby the secondary valve will move to application position and connect a pressure supply independent of the auxiliary reservoir to the brake cylinder upon a reduction of brake pipe pressure independently of the main valve device; means whereby the secondary valve will maintain 120 the brake cylinder pressure at a predetermined ratio to the brake pipe reduction, said secondary valve moving to release position when the brake cylinder pressure exceeds the predetermined ratio to the brake pipe re- 125 130

duction and moving to application position when the brake cylinder pressure is below the predetermined ratio to the brake pipe reduction; and means whereby the main and 5 secondary valves will be moved to release position upon an increase of brake pipe pressure.

45. An air brake apparatus comprising an emergency reservoir; an auxiliary reservoir; 10 a brake cylinder; a brake pipe; a main valve device; a secondary valve device; means whereby the main valve device will operate upon a reduction of brake pipe pressure to connect the auxiliary reservoir to the brake cylinder and then close said communication upon a substantial equalization of brake pipe and auxiliary reservoir pressures; means whereby the secondary valve will move to 15 application position and connect a pressure supply independent of the auxiliary reservoir to the brake cylinder upon a reduction of brake pipe pressure; means whereby the secondary valve will maintain the brake cylinder pressure at a predetermined ratio 20 to the brake pipe reduction, said secondary valve moving to release position when the brake cylinder pressure exceeds the predetermined ratio to the brake pipe reduction and moving to application position when the 25 brake cylinder pressure is below the predetermined ratio to the brake pipe reduction; means whereby the main and secondary valves will be moved to release position upon an increase of brake pipe pressure; a manually 30 operable release-governing valve; and means whereby the release-governing valve in one position will render the main slide valve device controlling in release operations and in another position will render the secondary valve device controlling in release operations, whereby when the secondary valve is controlling in release operations the brake cylinder pressure will be released in direct ratio to the increase in brake 45 pipe pressure.

46. An air brake apparatus comprising an emergency reservoir, an auxiliary reservoir, a brake pipe, a brake cylinder, main valve means subject to brake pipe pressure and 50 auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressure in the brake pipe and in the auxiliary reservoir whereby a certain volume of air will be discharged from 55 the auxiliary reservoir to the brake cylinder for a given brake pipe reduction, said main valve means operating upon an increase of brake pipe pressure to connect the brake cylinder to a main exhaust port, means oper-

ating upon an increase of brake pipe pressure to slowly release brake cylinder pressure through a secondary exhaust port and independent of the main exhaust port and at a uniform rate without regard to the degree of increased brake pipe pressure, and manually operable means in one position rendering the main exhaust means ineffective and the secondary exhaust means effective and in another position rendering the main exhaust means effective and the secondary 70 exhaust means ineffective.

47. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the brake pipe and in the auxiliary reservoir 90 whereby a certain volume of air will be discharged from the auxiliary reservoir to the brake cylinder for a given brake pipe reduction, a secondary independent valve controlling a restricted secondary exhaust port 95 adapted to slowly release brake cylinder pressure upon an increase in brake pipe pressure for a release of the brakes, and means controlled by variations in brake pipe pressure and subject to brake cylinder and emergency reservoir pressures for actuating said independent valve.

48. A triple valve for air brake apparatus comprising a main slide valve, a graduating valve, a piston connected to said valves and subject on one side to brake pipe pressure and on its other side to auxiliary reservoir pressure and operating upon an increase of brake pipe pressure to move the said valves to release position to connect the 110 brake cylinder to a main exhaust port and to open communication from the brake pipe to auxiliary reservoir, and operating upon a reduction of brake pipe pressure to move said valves to application position to connect the auxiliary reservoir to the brake cylinder and to close communication from the brake pipe to auxiliary reservoir, said communication with the brake cylinder being closed upon an equalization of pressures in the 115 brake pipe and in the auxiliary reservoir whereby a certain volume of air will be discharged from the auxiliary reservoir to

the brake cylinder for a given brake pipe reduction, a secondary independent valve operating upon a decrease in brake pipe pressure to connect an air supply to the 5 brake cylinder and operating upon an increase in brake pipe pressure to release position to connect the brake cylinder to atmosphere through a secondary port, means controlled by brake pipe and brake cylinder pressures opposed to the pressure of an 10 emergency reservoir for actuating said independent valve, and means whereby said pressure controlling valve will maintain the brake cylinder pressure in direct proportion to the brake pipe reduction.

49. A triple valve for air brake apparatus comprising a main slide valve, and a piston connected to said valve and subject on one side to brake pipe pressure and on its other 20 side to auxiliary reservoir pressure and operating upon an increase of brake pipe pressure to move the main valve to release position and operating upon a reduction of brake pipe pressure to move said valve to application position to connect the auxiliary reservoir to the brake cylinder, in combination with a pilot valve controlled by variations in brake pipe and brake cylinder pressures and subject to emergency reservoir 30 pressure, the brake cylinder pressure moving said pilot valve to service lap position and the emergency reservoir pressure moving said pilot valve to release lap position; and means whereby the brake cylinder pressure 35 will be built up by cycling operations.

50. An air brake apparatus comprising an emergency reservoir, an auxiliary reservoir, a brake cylinder, a brake pipe, a main valve device, a pilot valve device, means whereby the main valve device will operate upon a reduction of brake pipe pressure to connect the auxiliary reservoir to the brake cylinder and then close said communication upon a substantial equalization of brake pipe and auxiliary reservoir pressures, means whereby the pilot valve will move to application position and connect an air supply to the brake cylinder upon a reduction of brake pipe pressure, means whereby the pilot valve 45 will maintain the brake cylinder pressure at a predetermined ratio to the brake pipe reduction, said pilot valve moving to release position when the brake cylinder pressure exceeds the predetermined ratio to the brake pipe reduction and moving to application 55 position when the brake cylinder pressure is below the predetermined ratio to the brake pipe reduction, and means whereby the main and pilot valves will be moved to release position upon an increase of brake pipe pressure.

51. An air brake apparatus comprising an emergency reservoir, an auxiliary reservoir, a brake pipe, a brake cylinder, main valve 60 means subject to brake pipe pressure and

auxiliary reservoir pressure and operating upon a reduction in brake pipe pressure to open communication between the auxiliary reservoir and the brake cylinder and to close communication between the brake pipe and auxiliary reservoir, said communication with the brake cylinder being closed upon an equalization of pressure in the brake pipe and in the auxiliary reservoir whereby a certain volume of air will be discharged from the auxiliary reservoir to the brake cylinder for a given 70 brake pipe reduction, said main valve means operating upon an increase of brake pipe pressure to connect the brake cylinder to a main exhaust port, a 75 secondary valve means operating upon a reduction of brake pipe pressure to place an air supply in communication with the brake cylinder and close said communication when a predetermined brake cylinder pressure is secured from the auxiliary reservoir and said air supply, and operating upon an increase of brake pipe pressure to slowly release brake cylinder pressure to a secondary 80 exhaust port and independent of the main exhaust port, said secondary valve means being controlled by variations in brake pipe and brake cylinder pressures and subject to emergency reservoir pressure, manually operable means in one position rendering the 85 main exhaust means ineffective and the secondary exhaust means effective and in another position rendering the main exhaust means effective and the secondary exhaust means ineffective, and means whereby said 90 secondary valve will in all positions of the said manually operable means establish and maintain the brake cylinder pressure in direct proportion to a given brake pipe pressure 95 reduction and will, when the main exhaust is ineffective, reduce and maintain brake cylinder pressure in direct proportion to a given increase in brake pipe pressure.

52. A triple valve for air brake apparatus comprising a main slide valve; a graduating valve; a piston connected to said valves and subject on one side to brake pipe pressure and on its other side to auxiliary reservoir pressure and operating upon an increase of 100 brake pipe pressure to move the said valves to release position to connect the brake cylinder to a main exhaust port and to open communication from the brake pipe to auxiliary reservoir, and operating upon a reduction of 105 brake pipe pressure to move said valves to application position to connect the auxiliary reservoir to the brake cylinder and to close communication from the brake pipe to auxiliary reservoir, said communication with the 110 brake cylinder being closed upon an equalization of pressures in the brake pipe and in the auxiliary reservoir whereby a certain volume of air will be discharged from the auxiliary reservoir to the brake cylinder for a given 115 brake pipe reduction; a secondary independent 120 valve.

65 means subject to brake pipe pressure and

ent valve controlling a restricted exhaust and adapted to slowly release brake cylinder pressure upon an increase in brake pipe pressure for a release of the brakes; and means controlled by variations in brake pipe and brake cylinder pressures an subject to emergency reservoir pressure for actuating said independent valve.

53. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, in combination with a 20 pilot valve controlled by variations in brake pipe and brake cylinder pressures and subject to emergency reservoir pressure, a diaphragm subject to trapped brake cylinder pressure when the main slide valve is in service position, said trapped pressure opposing the brake cylinder pressure initially controlling the pilot valve, whereby the brake cylinder pressure will be built up during cycling operations.
54. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with automatically operating means to build up brake cylinder pressure by cycling operations, the extent of the build-up of brake cylinder pressure depending upon the rapidity of the cycling operations, said automatically operating means being controlled by variations in brake pipe and brake cylinder pressures and subject to emergency reservoir pressure; and a release governing valve having two positions, said release governing valve in one position preventing the build-up of brake cylinder pressure and in its other position permitting the said build-up of brake cylinder pressure.
55. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, in combination with automatically operating means to build up brake cylinder pressure by cycling operations, the extent of the build-up of brake cylinder pressure depending upon the rapidity of the cycling operations, said automatically operating means being controlled by variations in brake pipe and brake cylinder pressures and subject to emergency reservoir pressure.

sures and subject to emergency reservoir pressure.

55. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, and provided with automatically operating means to build up brake cylinder pressure by cycling operations, the extent of the build-up of brake cylinder pressure depending upon the rapidity of the cycling operations, said automatically operating means being controlled by variations in brake pipe and brake cylinder pressures and subject to emergency reservoir pressures; and a release governing valve having two positions, said release governing valve in one position preventing the build-up of brake cylinder pressure and in its other position permitting the said build-up of brake cylinder pressure.

56. A triple valve for air brake apparatus comprising a main slide valve, and a piston connected to said valve and subject on one side to brake pipe pressure and on its other side to auxiliary reservoir pressure and operating upon an increase of brake pipe pressure to move the main valve to release position and operating upon a reduction of brake pipe pressure to move said valve to application position to connect the auxiliary reservoir to the brake cylinder, in combination with means operated by reductions of and increases in brake pipe pressure to build up the brake cylinder pressure, said means being controlled by variations in brake pipe and brake cylinder pressures and subject to emergency reservoir pressure.

In testimony whereof I hereunto affix my signature.

SPENCER G. NEAL.
